US00D527596S

(12) **United States Design Patent** (10) **Patent No.:** **US D527,596 S**
(45) **Date of Patent:** **** Sep. 5, 2006**

(54) **RECIPROCATING SAW**

(75) Inventor: **Paolo Andriolo**, Vicenze (IT)

(73) Assignee: **Positec Power Tools (Suzhou) Co., Limited**, Suzhou (CN)

(**) Term: **14 Years**

(21) Appl. No.: **29/201,743**

(22) Filed: **Mar. 19, 2004**

(30) **Foreign Application Priority Data**

Sep. 23, 2003 (CN) 03 3 54186

(51) **LOC (8) Cl.** **08-03**

(52) **U.S. Cl.** **D8/64**

(58) **Field of Classification Search** D8/69, D8/68, 67, 66, 65, 64, 62, 61; 30/92, 394, 30/393, 392, 377, 376, 371; 74/50, 49; 173/217, 173/216; 83/699.21; 446/145

See application file for complete search history.

(57) **CLAIM**

The ornamental design for a reciprocating saw, as shown and described.

DESCRIPTION

FIG. 1 is a first perspective view of a reciprocating saw of the present design;

FIG. 2 is a second perspective view of a reciprocating saw of the present design;

FIG. 3 is a first side view of a reciprocating saw of the present design;

FIG. 4 is a second side view of a reciprocating saw of the present design;

FIG. 5 is a first end view of a reciprocating saw of the present design;

FIG. 6 is a second end view of a reciprocating saw of the present design; and

FIG. 7 is a top view of a reciprocating saw of the present design; and,

FIG. 8 is a bottom view of a reciprocating saw of the present design.

1 Claim, 7 Drawing Sheets

FIG. 1

FIG. 2

FIG. 3

FIG. 4

FIG. 5

FIG. 6

FIG. 7

FIG. 8
